UNITED STATES PATENT OFFICE

FRITZ GÜNTHER AND JOSEPH NÜSSLEIN, OF LUDWIGSHAFEN-ON-THE-RHINE, GERMANY, ASSIGNORS TO I. G. FARBENINDUSTRIE AKTIENGESELLSCHAFT, OF FRANKFORT-ON-THE-MAIN, GERMANY, A CORPORATION OF GERMANY

SOAP PREPARATION

No Drawing. Application filed May 29, 1926, Serial No. 112,675, and in Germany June 2, 1925.

It is known that soaps (which term is hereinafter used in a broad sense including soft soaps, grain soaps, resin soaps, sulfonated castor oil or the salts thereof such as Turkey 5 red oil and the like) cannot be employed in acid baths or in baths containing calcium or magnesium salts, as they are decomposed with the separation of free fatty acids or with the formation of insoluble salts. Also, soap 10 cannot be employed in salt water, for example sea-water.

We have now found that also in the above-mentioned acid baths and baths containing calcium or magnesium salts or salt water no 15 separation of fatty acids or insoluble salts occurs and that accordingly the soaps are rendered useful therein, provided the soaps or the baths contain aromatic sulfonic acids 20 possessing a high wetting power. As examples of such aromatic sulfonic acids we mention sulfonic acids of aromatic compounds containing hydrocarbon residues in their molecule, such as may be obtained for example by condensing aromatic sulfonic 25 acids with aliphatic, hydroaromatic or aromatic-aliphatic alcohols, such as isopropyl alcohol, butyl alcohols, cyclo-hexanol, benzyl-alcohol and the like. The side chains may also link together two aromatic nuclei as is 30 the case for instance in the condensation products of formaldehyde with naphthalene sulfonic acids. The said sulfonic acids may also contain other substituents such as halogen atoms or nitro or amino or hydroxyl 35 groups and the side chain may also be attached to such substituents as for example in amyl-naphthylamine sulfonic acids and the like. The aromatic sulfonic acids may be employed in the state of free acids or of salts.

40 For example, soap may be employed in the process of dyeing in an acid bath by adding an aromatic sulfonic acid possessing a high wetting power, and very even dyeings are thereby obtained; it is possible to use even such 45 dyestuffs which hitherto could only find restricted use on account of their small capability of producing even dyeings; further, the goods are penetrated with the color more thoroughly than without the said additions, 50 the fastness to rubbing is increased and the

time necessary for dyeing is diminished. Further, by our present invention wool fibre is protected from being damaged by alkalis as it can be washed and fulled in an acid bath, whereby often also a better result is obtained 55 than with the methods heretofore employed.

The sulfonic acid of the character described or a salt thereof may be added to the bath containing a soap such as dyeing baths, carbonization baths, i. e. baths containing sulfuric acid in a strength of from 2 to 4° Baumé, fulling baths, washing or bleaching baths and the like, or mixtures of soaps with the sulfonic acids or their salts may be prepared beforehand. The said soaps may be 60 neutral, alkaline or superfatted, and they may be employed in solution, or in the form of a paste or in the solid form. These preparations have the advantage of being easily 65 stored or shipped and can be applied in a very simple manner. They possess the desirable properties of both the soaps and the sulfonic acids, and are especially stable against acid and hard or salt water. They produce a good 70 lather with aqueous solutions containing acids or calcium or magnesium salts or similar obnoxious components such as produce 75 precipitations with soaps, and thus counteract their effect and are capable of easily wetting. They can be employed for example 80 for washing and cleaning purposes with water containing calcium or other salts or as an addition to dyeing baths containing acids or obnoxious salts. They are also very suitable 85 for use with sea-water.

The said mixtures can be prepared in any 90 desired manner, for example by heating a soap until it has entirely melted, and mixing the melt with the sulfonic acid or its salt or with a concentrated solution thereof or by kneading the soap with the dry salt and pressing the mixture to cakes or by mixing both in a powdery state or by adding the sulfonic acid during the saponification process. A 95 mixture which is very suitable for most purposes consists for example of 80 parts of ordinary soap and 20 parts of a sulfonic acid of the character mentioned or a salt thereof. In case of water containing only small quan- 100

tities of acid or the above mentioned obnoxious salts a smaller amount of the sulfonic acid or its salt may be sufficient while in extremely difficult cases greater quantities thereof than indicated above may be advisable. The mixture may also contain further purifying agents as for example borax, alkali metal silicates or organic solvents such as glycerol, benzine, alcohols, cyclohexanol and the like.

10 In some cases, it is advantageous to employ the soap and sulfonic acid in conjunction with sulfite cellulose waste liquor which may be added to the bath or incorporated to the preparation of soap and sulfonic acid.

15 The following examples will further illustrate how our present invention may be carried out in practice, but the invention is not limited to these examples.

20 *Example 1*

A dye-bath is prepared containing for 100 kilograms of woollen cloth 0.5 per cent of fast yellow G for wool, 0.25 per cent of 25 supramine red B and 0.2 per cent of anthraquinone blue SR extra and, in each litre, 2 grammes of soap and 2 grammes of isopropylated naphthalene sulfonic acid. The cloth is dyed in the usual manner after adding 3 30 per cent of sulfuric acid to the bath. The wool is wetted very rapidly and the dyeing is easily finished in the course of one hour. A dyeing is produced which fulfills all requirements as to evenness, fastness to rubbing 35 and penetration with color.

The bath may also contain sulfite cellulose waste liquor.

Example 2

40 50 kilograms of woollen cloth are fulled with a soap solution containing 100 grams of a neutral soap and 45 grams of isopropylated naphthalene sulfonic acid per litre. The cloth so treated is excellently fulled without any 45 damage being done to the fibre. When alkaline soaps are employed, the soap solutions are first to be neutralized in any suitable manner, and such neutralization may also be effected by the said sulfonic acid.

50 The said additions are also of great advantage when used together with Turkey red oil of which from 1 to 10 grams per litre may be employed.

55 *Example 3*

50 kilograms of soap are melted or kneaded in the cold with 50 kilograms of butylated naphthalene sulfonic acid sodium salt and 20 60 kilograms of concentrated sulfite cellulose waste liquor. Water may be added in sufficient quantities, if necessary, to allow of a uniform mixing. The product so obtained may be used for the washing and fulling of 65 goods containing acids even in hard water

without any fatty acid or salts thereof being precipitated.

Example 4

10 kilograms of dry soap are intimately 70 mixed with 25 kilograms of the sodium salt of isopropylated naphthalene sulfonic acid. 1 or 2 grams of this mixture dissolved in five times the weight of water are added to each litre of a carbonizing bath. In spite of the 75 carbonization process the goods remain elastic and supple by reason of their taking up fatty acids.

The mixture of soap and the sulfonic acid salt may also be mixed with solvents, for example with 5 kilograms of ethylene glycol mono-ethyl-ether, whereby the solubility of 80 the soap in the acid bath is increased.

Instead of the sodium salt of isopropylated naphthalene sulfonic acid, the salts of butylated naphthalene sulfonic acids may be employed.

Example 5

100 kilograms of crude wool (wool in the 90 grease) are treated with an acid washing bath containing in each litre about 6 grams of grain soap, 10 grams of butyl-naphthalene-sulfonic acid and 4 grams of sodium bisulfite. The wool is treated at temperature 95 of about 20° to 35° C. for about half an hour. It is excellently washed and degreased and at the same time it is bleached to a beautiful white by the action of the bisulfite. In order to increase the efficiency, washing may also 100 be carried out for example at about 50 to 90° C., for example in nearly boiling baths.

Instead of grain soap, about the same quantity of resin soap and, instead of butyl-naphthalene-sulfonic acid, other aromatic sulfonic acids of high wetting power, for example di-butyl-aniline sulfonic acid, condensation products of cresol-sulfonic acid with formaldehyde, the sulfonation products of the residues obtained by the distillation of 105 coal tar, after the anthracene has been distilled off, and the like, may be employed.

We claim:

1. The process of treating articles with soaps which consists in employing a bath containing soap and an aromatic sulfonic acid containing hydrocarbon residues possessing a high wetting power.

2. The process of treating articles with soaps which consists in employing a bath containing a soap and a naphthalene sulfonic acid containing alkyl groups with at least 3 carbon atoms.

3. The process of treating articles with soaps which consists in employing a bath containing a soap, an aromatic sulfonic acid containing hydrocarbon residues of high wetting power and sulfite cellulose waste liquor.

4. A soap preparation comprising a soap and an aromatic sulfonic acid containing 130

hydrocarbon residues possessing a high wetting power.

5. A soap preparation comprising a soap and a naphthalene sulfonic acid containing alkyl groups with at least 3 carbon atoms.
6. A soap preparation comprising a soap, an aromatic sulfonic acid containing hydrocarbon residues of high wetting power and an organic solvent.
10. A soap preparation comprising a soap, an aromatic sulfonic acid containing hydrocarbon residues of high wetting power and sulfite cellulose waste liquor.
15. A soap preparation comprising a soap, an aromatic sulfonic acid containing hydrocarbon residues of high wetting power, an organic solvent and sulfite cellulose waste liquor.

In testimony whereof we have hereunto
20 set our hands.

FRITZ GÜNTHER.
JOSEPH NÜSSLEIN.
